SHIELDING DEVICE

Paul Strehmel, Berlin-Siemensstadt, Germany,
assignor to Siemens & Halske, Aktiengesellschaft,
Siemensstadt, near Berlin, Germany,
a corporation of Germany

Application March 12, 1935, Serial No. 10,639
In Germany March 10, 1934

14 Claims. (Cl. 123—169)

My invention relates to a shielding device adapted for use in connection with spark plugs to prevent the radiation of electric waves. One of the known types of devices of this character was designed in such a manner that its lower part was fastened to the motor upon tightening the spark plug in place, this part being provided at the upper end with a screw joint or the like arranged to complete the structure. In another known arrangement, a member carrying a locking spring is secured to the spark plug, pressing into place a shielded cable socket of suitable design.

These structures consist at least of two separate members which are assembled upon applying them to the spark plug. The various parts of the device must be individually dismantled and assembled, respectively, upon removal or attachment of the corresponding spark plug.

Another known type of shield may be fitted as a whole over the spark plug and removed from the same. It consists of two cylindrical metal sleeves fitted into each other, by means of which the device may be secured to the hexagon of the gland nut of the spark plug. The device comprises among other structural parts various expensive metal members which are under the action of a strong spring; moreover, the diameter of this structure is larger than the outer diameter of the hexagonal portion of the spark plug. Accordingly, where crowded conditions prevail it can not be placed over the spark plug at all or only with difficulties.

The object of my invention is to eliminate the above noted drawbacks and is accomplished by employing a shielding device consisting of two metal sleeves fitted into each other, the outer sleeve having a diameter smaller than the outer diameter of the hexagonal portion of the spark plug and carrying at the upper end a screw joint, the lower end thereof being designed in the form of a hexagon having ports for the passage of the corners of the hexagonal portion of the plug body. Consequently, the sleeve may be placed over the spark plug from above and secured to the hexagonal portion of the spark plug after a partial rotation by means of the inner sleeve and of the screw joint.

In the accompanying drawing which shows an embodiment of my invention in diagrammatic form, and in which similar reference characters indicate similar parts, Fig. 1 is an elevational view of the spark plug with the shield made according to my invention shown in vertical sectional view; Fig. 2 is a transversal sectional view taken on the line A—B of Fig. 1; Fig. 3 shows the

individual parts of the device dismantled and placed separately in a row; Fig. 4 shows a detail part; and Fig. 5 represents a side view of the part shown in Fig. 4.

1 denotes the metal sleeve forming the shield proper. It is fitted in a metal sleeve 2 having ports 3 at the lower end with webs 4 lying therebetween. The lower end of the metal sleeve 2 is designed in the form of a hexagon corresponding to the hexagonal portion of the spark plug. The upper end of the sleeve 2 is provided with a threaded portion for engaging the screw joint or closure 5. Inside the metal sleeve 1 is placed a cap 6 of suitable insulating material (e. g., moulded, pressed or ceramic material) having a channel 7 extending through its upper part for the reception of the end of an electric cable. A suitable terminal projection or extension 8 is provided at the inner end of the channel or duct in order to establish the connection between the conductors of the cable and the central electrode of the plug. This terminal extension is designed so as to form at the rear thereof a hollow rivet, around the shaft of which is secured the end of a metal spring 9. By pressing the terminal 8 against the inner back wall of the cap 6 the hollow rivet is expanded, thereby establishing the connection with the spring 9, the other end of which engages the central electrode of the spark plug as shown.

30 A bushing member 10 which receives the cable (not shown) is arranged in the metal sleeve. Since the channel for the cable lies within the cap 6 and not exteriorly thereof as is usually the case the connection of the cable may also be easily effected, even if the end of the cable is short. The member 10 is secured to the metal sleeve 1 by means of the grooves 11 provided on the neck of member 10 and engaging the edges of a cut 35 away portion of the sleeve.

40 The assembly of the shielding device is effected by inserting the metal sleeve 1 from below into the metal sleeve 2. The member 10 is placed in position into the opening 12 of the metal sleeve 2 so that upon a further insertion of the sleeve 1 the connection of both parts is established. To prevent the metal sleeve 1 from falling out, the lower edge 13 of the metal sleeve 2 is pressed between the webs 4 somewhat inwardly so that the metal sleeve 1 is firmly held in position. The cap 50 6 of insulating material is then inserted into the metal sleeve 1. After the insertion of the end of the cable, the cap 6 is also prevented from falling out. Finally, the screw joint or closure 5 is screwed into the sleeve 2. The loosening or 55

inadvertent displacement of the screw joint 5 may be prevented in any suitable manner.

The shielding device is passed over the spark plug from above until the lower edge 13 lies below the hexagonal portion of the spark plug and is then rotated approximately 30°. When screwing the joint 5 into the metal sleeve 2 the metal sleeve 1 is pressed in a downward direction until it rests on the hexagonal portion of the spark plug. Upon further screwing in the joint 5 into the metal sleeve 2, the latter is caused to move in the upward direction until the lower edge thereof firmly contacts with the lower surface of the hexagonal portion of the spark plug. The device is thus firmly clamped on the hexagon of the spark plug. An undesirable rotation of the shielding device in the one direction is prevented by teeth 14 arranged at the lower edge of the metal sleeve 2 which engage the surface of the hexagonal portion of the spark plug, whereas a rotation in the other direction is prevented by the webs 4 which are somewhat twisted and which also contact with the surfaces of the hexagonal portion of the spark plug. Instead of the teeth 14 inclined surfaces may be employed.

The shielding device has the advantage that it need only be moved in the axial direction when being placed over or removed from the spark plug. Furthermore, since its diameter is smaller than the outer diameter of the hexagonal portion of the spark plug, the cap like device may be easily placed over the spark plug even in the case of very crowded conditions. The device consists substantially of simple, light and economical parts, particularly of thin-walled tubes, the manufacture of which requires no particular methods, and can be manipulated easily and placed over or removed from the spark plug with one hand. If the screw joint 5 is loosened, the entire arrangement can be rotated a certain extent and placed in position for easy removal. Even when securing the shield to the spark plug it is only necessary to pass it over the hexagonal portion of the spark plug and to tighten the screw joint. The metal sleeve 2 is then caused to rotate slightly until the clamping and locking on the hexagon is accomplished.

Due to the design of the lower portion of the metal sleeve 2 in the form of a hexagon the device may be placed over the spark plug in six different positions so that it is possible to introduce the cable into the shielding device easily and from any desired angle. Slight changes which might be necessary may be brought about by rotating the bushing member 18 within the opening 12 of the metal sleeve 2.

In order to prevent a loosening of the screw joint 5 a locking device 15 may be provided, comprising a spring secured to the body of the outer sleeve 2 which is adapted to engage any of the notches on the peripherally knurled closure 5 as shown.

In order to ensure cooling of the spark plugs in spite of the shield the metal sleeve 1 may be provided at the lower end thereof with suitably screened ports. The shielding effect is thereby not impaired, since the heat may be dissipated through the screening (wire nettings and the like) and through the ports 3 into the metal sleeve 2.

I claim as my invention:—

1. A shielding device for attachment to spark plugs having a hexagon comprising, an outer cylindrical metal sleeve the diameter of which is less than the edgewise diameter of the hexagon

of said spark plug, one end of said sleeve forming a hexagon arranged for placing said sleeve over the hexagon of said spark plug, ports in said hexagon on said sleeve for receiving the edges of said spark plug hexagon upon rotating said sleeve thereon, an inner sleeve disposed in said outer sleeve, and a screw joint at the other end of said outer sleeve for clamping said device onto said spark plug hexagon by means of said inner sleeve.

2. A shielding device for attachment to spark plugs having a hexagon comprising, an outer cylindrical metal sleeve the diameter of which is less than the edgewise diameter of the hexagon of said spark plug, one end of said sleeve forming a hexagon arranged for placing said sleeve over the hexagon of said spark plug, ports in said hexagon on said sleeve for receiving the edges of said spark plug hexagon upon rotating said sleeve thereon, an inner sleeve disposed in said outer sleeve, a screw joint at the other end of said outer sleeve for axially securing said device to said spark plug hexagon by means of said inner sleeve, and means on said outer sleeve for locking said device against rotation.

3. A shielding device for attachment to spark plugs having a hexagon comprising, an outer cylindrical metal sleeve the diameter of which is less than the edgewise diameter of the hexagon of said spark plug, one end of said sleeve forming a hexagon arranged for placing said sleeve over the hexagon of said spark plug, ports in said hexagon on said sleeve for receiving the edges of said spark plug hexagon upon rotating said sleeve thereon, webs between said ports, said webs being twisted to secure rotation of said sleeve on said spark plug hexagon of about 30°, an inner sleeve disposed in said outer sleeve, and a screw joint at the other end of said outer sleeve for clamping said device onto said spark plug hexagon by means of said inner sleeve.

4. A shielding device for attachment to spark plugs having a hexagon comprising, an outer cylindrical metal sleeve the diameter of which is less than the edgewise diameter of the hexagon of said spark plug, one end of said sleeve forming a hexagon arranged for placing said sleeve over the hexagon of said spark plug, ports in said hexagon on said sleeve for receiving the edges of said spark plug hexagon upon rotating said sleeve thereon, ribs between said ports, the material of said sleeve at said end thereof being pressed inwardly intermediate of said ribs, an inner sleeve disposed within said outer sleeve, said inner sleeve being held in place in one direction by said inwardly pressed material of said end of the outer sleeve, and a screw joint at the other end of said outer sleeve for clamping said device onto said spark plug hexagon by means of said inner sleeve.

5. A shielding device for attachment to spark plugs having a hexagon comprising, an outer cylindrical metal sleeve the diameter of which is less than the edgewise diameter of the hexagon of said spark plug, one end of said sleeve forming a hexagon arranged for placing said sleeve over the hexagon of said spark plug, ports in said hexagon on said sleeve for receiving the edges of said spark plug hexagon upon rotating said sleeve thereon, an inner sleeve disposed in said outer sleeve, a screw joint at the other end of said outer sleeve for clamping said device onto said spark plug hexagon by means of said inner sleeve, and means for locking said screw joint.

6. A shielding device for attachment to spark

plugs having a hexagon comprising, an outer cylindrical metal sleeve the diameter of which is less than the edgewise diameter of the hexagon of said spark plug, one end of said sleeve forming a hexagon arranged for placing said sleeve over the hexagon of said spark plug, ports in said hexagon on said sleeve for receiving the edges of said spark plug hexagon upon rotating said sleeve thereon, an inner sleeve disposed in said outer sleeve, a screw joint at the other end of said outer sleeve for clamping said device onto said spark plug hexagon by means of said inner sleeve, an insulating cap disposed within said inner sleeve, a lateral duct in said cap for receiving the end of an electric conductor, and terminal means within said duct at the inner end thereof for establishing connection between said cable and the central electrode of said spark plug.

7. A shielding device for attachment to spark plugs having a hexagon comprising, an outer cylindrical metal sleeve the diameter of which is less than the edgewise diameter of the hexagon of said spark plug, one end of said sleeve forming a hexagon arranged for placing said sleeve over the hexagon of said spark plug, ports in said sleeve for receiving the edges of said spark plug hexagon upon rotating said sleeve thereon, an inner sleeve disposed in said outer sleeve, a screw joint at the other end of said outer sleeve for clamping said device onto said spark plug hexagon by means of said inner sleeve, an insulating cap disposed within said inner sleeve, a lateral duct in said cap for receiving the end of an electric conductor, terminal means within said duct at the inner end thereof for establishing connection between said cable and the central electrode of said spark plug, one end of said terminal means forming a hollow rivet arranged to expand by axial displacement, and conductor means for connecting said end of the terminal means with the central electrode of said spark plug.

8. In combination with a spark plug having a hexagon, a shielding device for attachment to the hexagonal portion thereof, said device comprising, a tubular sleeve one end of which is arranged to be slipped over said hexagonal portion and ports in said end of said sleeve arranged for rotating said sleeve relative to said hexagonal portion whereby the edges thereof enter into said ports, a tubular companion sleeve disposed within said first sleeve, and closure means at the other end of said first sleeve arranged to actuate the second sleeve for locking said hexagonal portion within said ports of said first sleeve.

9. In combination with a spark plug having a hexagon, a shielding device for attachment to the hexagonal portion thereof, said device comprising, a tubular sleeve one end of which is arranged to be slipped over said hexagonal portion, and ports in said end of said sleeve arranged for rotating said sleeve relative to said hexagonal portion whereby the edges thereof enter into said ports, a tubular companion sleeve disposed within

said first sleeve, closure means at the other end of said first sleeve arranged to actuate said second sleeve for axially locking said shielding device on said hexagonal portion by means of said ports in said first sleeve, and means on said first sleeve for securing said device against radial displacement. 5

10. In combination with a spark plug having a hexagon, a shielding device for attachment to the hexagonal portion thereof, said device comprising, a tubular sleeve one end of which is arranged to be slipped over said hexagonal portion and ports in said end of sleeve arranged for rotating said sleeve relative to said hexagonal portion whereby the edges thereof enter into said ports, a tubular companion sleeve disposed within said first sleeve, closure means at the other end of said first sleeve arranged to actuate said second sleeve for axially locking said shielding device on said hexagonal portion by means of 10 said ports in said first sleeve, means in said first sleeve for securing said device on said spark plug against radial displacement, an insulating member within said device and a lateral duct therein for receiving an electrical conductor, terminal 15 means on said duct for connection with said conductor, and means for connecting said terminal means with the electrode of said spark plug. 20

11. A shielding device for attachment to a spark plug having a wrench receiving portion comprising, in combination, an outer shell member, alternate projections and recesses at one end of said shell member for direct engagement with said wrench receiving portion of said plug, an inner tubular member disposed movably within 30 said shell outer member, and means at the other end of said shell member for moving said inner member relative to said outer member to secure the attachment of said device on said spark plug with said projections and recesses of said shell member surrounding said wrench receiving portion 35 thereof. 40

12. The structure defined in claim 11, particularly for a spark plug having a hexagon, wherein the end of said outer shell member having said alternate projections and recesses is arranged to be slipped over said hexagon, whereby said outer shell member may be rotated relative to said hexagon to enter the edges of said hexagon in said recesses. 45

13. The structure defined in claim 11, together with a unitary insulating member disposed within said inner tubular member, and terminal means in said insulating member connected to the electrode of said spark plug. 50

14. The structure defined in claim 11, together with a unitary insulating member disposed within said inner tubular member, terminal means in said insulating member, means connecting said terminal means with the electrode of said spark 60 plug, and a duct in said insulating member for receiving the end of a cable to be connected to said terminal means. 65

PAUL STREHMEL.
